UNITED STATES PATENT OFFICE.

JOHN M. DODD, OF CHICAGO, ILLINOIS, ASSIGNOR TO PEERLESS MANUFACTURING COMPANY, OF LOUISVILLE, KENTUCKY, A CORPORATION OF DELAWARE.

DESIGN FOR A PORTABLE BASKET-GRADE.

SPECIFICATION forming part of Design No. 35,216, dated October 22, 1901.

Application filed September 28, 1901. Serial No. 76,300. Term of patent 7 years.

To all whom it may concern:

Be it known that I, JOHN M. DODD, a subject of the King of Great Britain, (but having declared my intention of becoming a citizen 5 of the United States,) residing at Chicago, in the county of Cook and State of Illinois, have invented and produced a certain new and original Design for Portable Basket-Grates, (Case C,) of which the following is a full, clear, and exact description.

This invention relates to what is known in the trade as a "portable basket-grate" for fireplaces.

In the accompanying drawing, forming part 5 of this specification, the invention is illustrated in perspective view.

As shown in the drawing, the leading or material features of my design consist of angular corner posts or columns surmounted 10 by urns or vases and a grille-front between the posts, the spindles of which grilles are representations of conventional tulips set stem for stem, and also a segmental back

piece having a center wreath intersecting garlands and streamers in high relief. The posts 25 are shown as having longitudinally-fluted feet and beaded panels, and the grille has a fluted base-rail and a straight top rail, terminating in volutes or scrolls. A shell-like center piece depends from the center of the base-rail. The back piece has a peripheral molding and a reeded center piece above the wreath and from which the wreath and the garlands 30 apparently depend.

Having thus described my invention, what 35 I claim as new, and desire to secure by Letters Patent, is—

The design for a portable basket-grate, substantially as herein shown and described.

In testimony whereof I have hereunto set 40 my hand this 16th day of September, A. D. 1901.

JOHN M. DODD.
